UNITED STATES PATENT OFFICE.

FERDINAND BUCHSTEIN, OF MINNEAPOLIS, MINNESOTA.

ARTIFICIAL LEG.

1,107,893.

Specification of Letters Patent. Patented Aug. 18, 1914.

Application filed August 16, 1912. Serial No. 715,367.

To all whom it may concern:

Be it known that I, FERDINAND BUCHSTEIN, a citizen of the United States, residing at Minneapolis, in the county of Hennepin and State of Minnesota, have invented certain new and useful Improvements in Artificial Legs; and I do hereby declare the following to be a full, clear, and exact description of the invention, such as will enable others skilled in the art to which it appertains to make and use the same.

My invention relates to artificial legs and has for its object to improve the same in several important particulars, but more especially is directed to the improved connections for producing natural forward swinging movement of the lower leg section of an artificial leg constructed for application to upper leg amputations.

20 The improved leg is illustrated in the accompanying drawings wherein like characters indicate like parts throughout the several views.

Referring to the drawings, Figure 1 shows the improved artificial leg in front elevation, some parts being broken away and some parts being sectioned; Fig. 2 is a side elevation of the improved artificial leg, some parts being broken away and some parts being sectioned; Fig. 3 is an enlarged vertical section taken approximately on the line $x^3 x^3$ on Fig. 2, and showing one of the connections removed from the artificial leg; and Fig. 4 is a detail in vertical section taken approximately on the line $x^4 x^4$ on Fig. 1.

The numeral 1 indicates the lower leg section, the numeral 2 the upper leg section and the numeral 3 the foot of the artificial leg, which parts may be of the usual or any suitable construction, the foot being connected to the lower end section by an ankle joint 4 and the upper and lower leg sections being connected by a suitable knee joint 5.

45 The numeral 6 indicates the shoulder strap cords, which in accordance with one feature of the invention, are passed through adjustable cord guides. These cord guides, as shown, are made up each of a tubular guide sleeve 7 and rectangular guide loop 8 connected by a tubular rivet 9. Preferably, said parts 7 and 8 are made of leather. The shoulder strap cords 6 are passed through 50 the guide sleeves 7, and an anchoring strap 10, preferably of leather, is passed through

the guide loop 8. This anchor strap 10 surrounds the upper portion of the upper leg section 2 and is anchored thereto at several different points by screws 11, or other suitable devices. Between the screws 11, the anchor strap 10 is loose and has perforations 12, through which, and the tubular rivets 9, tie cords 13 are adapted to be passed to anchor the cord guides 7—8 with freedom for 60 adjustments circumferentially of the leg. This adjustment is important and will presently more fully appear, because it permits the leg to be adjusted and suspended from the shoulder straps with the foot of the artificial limb set at a desired angle of divergence. The upper ends of the cords 6 are formed with loops to which the shoulder straps may be conveniently attached.

The numeral 14 indicates strong elastic 75 straps which, at their lower ends, are anchored to the sides of the lower portion of the upper leg section 2, and at their free upper ends are secured to sheave brackets or heads 15, which latter are provided with 80 sheaves 16 hung upon the intermediate portions of the shoulder strap cords 6. Also, the backs of the brackets 15 are attached by screws 17, and otherwise, to the upper ends of so-called lower leg straps 18. These 85 knee straps 18 are extended downward in front of the knee joint pivot 5 and are passed through eyelets or perforations 19 formed in the front of the upper portion of the lower leg section 1. Also the straps 18 are 90 preferably passed through guide loops on the lower front portion of the upper leg section 2, afforded by straps 20 having their ends secured to the sides of the lower portion of the upper leg section 2. The lower 95 ends of the straps 18, after they are passed through the eyelets 19 are passed through suitable guides 21 secured on the rear intermediate portion of the interior of the lower leg section. The extreme inner ends of the 100 said straps 18 are attached to, or provided with elastic terminal straps 18^a that are anchored at 22 to the back of the lower leg section 1.

With the above described arrangements of 105 the elements of the leg, the action is substantially as follows: The shoulder straps need not be made of elastic material, inasmuch as the elasticity of the suspender made up of the shoulder strap cords 6 and elastic straps 14 will properly carry and hold up 110 the upper leg section 2 and maintain the

proper engagement thereof with the leg stump. When the foot of the artificial leg is lifted from the ground while the knee joint is bent, the lower leg straps 18 will be 5 put under tension by the upward pull on the shoulder strap cord, and hence, the lower leg section will be given a natural forward swinging movement into straight alinement with the upper leg section. Any excessive 10 pull on the straps 18 will simply stretch the elastic sections 18^a thereof.

It will be noted that the upper and lower 15 ends of the straps 18 are anchored or have their terminal connections on a line that extends at the rear of the knee joint 5, while the intermediate portions of the said straps are guided by, and act against portions of the leg sections 1 and 2 that are far ahead of the knee joint. This arrangement, of course, 20 causes tension on the straps 18 to exert a force in the direction to swing the foot forward to an extreme normal position, in respect to the upper leg section 2, shown in Fig. 2.

What I claim is:

1. In an artificial leg, the combination with upper and lower leg sections connected by a knee joint, of independent circumferentially adjustable cord guides on the upper portion of said upper leg section, and shoulder strap cords extended through said guides and connected to said lower leg section. 25

2. In an artificial leg, the combination with upper and lower leg sections connected by a knee joint, of an anchoring strap extended around the upper portion of said upper leg section and attached thereto, cord guides adjustably mounted on said anchoring strap, and shoulder strap cords extended through said guides and connected to said lower leg section. 30 35

In testimony whereof I affix my signature in presence of two witnesses.

FERDINAND BUCHSTEIN.
